UNITED STATES PATENT OFFICE.

WILLIAM L. BROOKS, OF ARDMORE, OKLAHOMA.

GAS STOVE.

Application filed February 21, 1928. Serial No. 256,025.

This invention relates to heaters employing gaseous fuel and has for its primary object the provision of an inexpensive device which will be so constructed that the heat may be projected from either side or both sides so as to effectually raise the temperature of the room in which the heater is located. The invention also has for its object the provision of a device which will be attractive in appearance and will be provided with means to prevent persons standing or passing near the heater reaching the flame with consequent serious injury. The invention also provides a structure in which efficient circulation of the heated air currents will be attained, and other objects of the invention will appear incidentally in the course of the following description.

In the accompanying drawing, which illustrates one embodiment of the invention,

Figure 1 is a perspective view of the heater, and

Fig. 2 is a vertical transverse section of the same.

In carrying out the invention, there are provided end plates 1, preferably of sheet metal, each of which has a short lateral extension 2 at each of its lower corners. Extending between the outer edges of the corresponding extensions are side strips 3 and secured in any approved manner to the extensions 2 and the side strips 3 at the junctions of the same are legs 4 whereby the device will be supported in spaced relation to the floor of the room to provide an open space through which air may pass to the burners and to rise through the device so as to cause circulation of the heat through and from the structure. The upper corners of the end plates 1 are connected by upper side strips 5 which may be ornamental as desired and are provided with inwardly projecting flanges 6 along their upper edges, as shown in Fig. 2. Resting on the flanges 6 and extending over the entire top of the structure is a cover 7 having openings 8 therethrough so that hot air rising through the device may escape into the room. The side edges of the cover are formed into beads 9 to impart an ornamental appearance to the heater and ornamental cap nuts 10 may be fitted on the ends of the securing bolts to further add to the attractive appearance of the device. It will be understood that the parts thus far described constitute a housing in which the

burners, indicated conventionally at 11, are disposed and the burners are arranged in two longitudinal series at opposite sides of the central longitudinal plane of the housing, the fuel being supplied to the burners through longitudinal pipes 12 each having one end extended through one end plate 1 and equipped with a cut-off valve 13 in the usual manner. A main supply pipe 14 leading from a supply tank or from the street main communicates with the burner pipes 12 through the valves in an obvious manner.

Attached to the upper edges of the side strips 3 are bottom plates which extend in a general upward direction inwardly from said strips and have their inner edge portions fitted about the several burners, as indicated at 15. These plates extend obliquely downwardly and outwardly from their inner edge portions to provide inclined portions 16 which have their upper surfaces highly polished so that they constitute reflectors whereby to throw out into the room any heat currents which may radiate thereover from the burner tips and the outer portions of these plates extend downwardly, as shown at 17, for a short distance and then extend outwardly to provide shelves 18 extending to and resting upon the edges of the side strips 3. I thus provide a lower partition which serves as a cover for the bottom portion of the casing and prevents objects falling onto the burner pipes to damage the same and cause leaks which might result disastrously. The peculiar formation of these partitions also aids in imparting an attractive finish to the heater. The extreme inner edges of the lower partitions are stepped or rabbeted, as shown at 19, and extending between the end plates and abutting these stepped terminals are upright backing plates 20 of sheet metal which serve as supports for asbestos mats 21, the lower edges of the mats being seated in the stepped portions 19, as clearly shown in Fig. 2. These mats may be secured to the backing plates 20 in any approved manner, and in order to guard against buckling of the backing plates, said plates are doubled upon themselves at their centers to form ribs or flanges 22 extending from end to end thereof. For a like purpose, the upper end portions of the backing plates are doubled upon themselves, as shown at 23, and are then extended inwardly to provide a top plate 24 having central openings 25 formed therethrough. It will be noted that the burner tips

11 are disposed adjacent and at the outer sides of the mats 21 so that the flame formed at the tips will play over the mats which will become incandescent and glow so that a large heat 5 radiating surface will be acquired and the heater, when in use, will give an appearance of warmth and cheerfulness which is greatly to be desired. The openings 25 through the top plate 24 permit the currents rising through 10 the housing to pass upwardly between the backing plates 20 and out to the cover 7 to escape through the openings 8 in the latter, and to reduce the buckling effect upon the cover a reinforcing plate or shell 26 is secured to the 15 under side of the same and extends between the end plates 1 immediately over the vertical planes of the backing plates and the mats. The lower edges of the upper side strips 5 are formed into re-entrant flanges 27, and flanges 20 28 on the lower edges of hood plates or deflectors 29 are interlocked with said re-entrant flanges. The hood plates 29 are provided at their ends with flanges 30 which bear against the end plates 1 of the housing and may be 25 riveted or otherwise rigidly secured thereto. The plates 29 converge upwardly and inwardly and terminate substantially in the vertical planes of the mats 21 at points midway between the mats and the cover 7. It will be 30 noted also that the lower edges of the upper side strips 5 are in a horizontal plane slightly below the horizontal plane of the upper edges of the mats and any heated currents which are not diverted into the room through the 35 openings between the respective strips 3 and 5 will be deflected inwardly within the housing and then permitted to escape through the openings 8.

Fenders are secured to and extend between 40 the end plates 1 across the open spaces between the respective side strips 3 and 5, and these fenders consist of longitudinal rods or stout wires 31, having their ends secured to the end plates in any approved manner, and vertical rods or wires 32 attached rigidly to the horizontal wires at intervals along the latter. The wires 31 are bowed inwardly at or 45 immediately adjacent their ends, while the vertical wires 32 are bowed inwardly at their upper and lower ends so that the fenders will 50 be offset outwardly from the housing and will also be so formed that they are not apt to catch in the clothing of persons standing or passing near the heater. The offset formation 55 will tend to prevent persons coming into contact with the heater accidentally and, consequently, the liability of persons being burnt is minimized.

From the foregoing description, taken in 60 connection with the accompanying drawing, it will be seen that I have provided an exceedingly simple and attractive device by the use of which a large room may be quickly heated and easily maintained at a comfortable temperature. Inasmuch as the device

will heat by both radiation and convection at both sides of the structure, the heater is especially adapted for placement in the center of a room or at other points remote from a side or end wall.

The stove has two separate burners either of which may be used independently of the other, or both burners may be used simultaneously as the conditions demand, thereby saving fuel and also space as you have the heating capacity of two stoves in one or one stove with just half the heat if you so desired. The construction of combining two burners in one stove operated at will makes a novel construction. The stove may be set in a partition, as in an office, and the room at either side of the partition heated without affecting the room at the other side.

Having thus described the invention, I claim:

1. A heater comprising an open bottom casing having lower side strips extending from end to end, partitions attached at their outer edges to the upper edges of said side strips and extending upwardly and inwardly therefrom, the inner edges of said partitions being stepped and spaced transversely of the casing, backing plates extending from end to end of the casing and abutting the stepped inner edges of the partitions, heat-radiating mats seated at their lower edges in the stepped edges of the partitions and supported by said plates, and burners mounted in the casing below the partitions and rising through the inner edge portions of the partitions at the outer sides of the radiating mats.

2. A heater comprising a casing having openings in its opposite sides, heat-radiating elements extending from end to end of the casing in the horizontal planes of said openings, burners supported in the casing adjacent the lower edges and the outer sides of said heat-radiating elements, and fenders extending from end to end of the casing across the openings in the sides thereof and consisting of longitudinal elements having their ends offset outwardly from the casing, and similarly spaced vertical elements carried by the longitudinal elements and, having their ends bowed inwardly toward the casing.

3. A heater comprising a casing having an open bottom and having upper and lower side strips extending from end to end thereof, heat-radiating members extending from end to end of the casing and spaced inwardly from the side strips, upwardly and inwardly converging deflectors attached at their outer lower edges to the lower edges of the upper side strips and having their inner upper edges disposed between the heat-radiating members and the top of the casing and in spaced relation to said members and the top, and partitions extending downwardly and outwardly from the lower edges of the radiating members to the upper edges of the lower side strips.

4. A heater comprising an open bottom casing, upper and lower side strips connecting the ends of the casing, partitions extending inwardly from the upper edges of the lower side strips and terminating in spaced relation to the medial longitudinal plane of the casing, radiating members extending from end to end of the casing along the inner edges of said partitions and providing a central circulating 10 space, reinforcing ribs on the inner opposed sides of said radiating members, a top plate connecting the upper ends of said members and having openings therethrough, a cover over the casing and spaced vertically from

the radiating members and top plate and having openings through its edge portions, a reinforcing plate on the under side of the cover along the medial longitudinal line thereof, deflectors extending inwardly and upwardly from the lower edges of the upper side strips 20 with their upper edges over the upper ends of the radiating members and spaced vertically from said members and from the cover, and burners located adjacent the lower edges of said radiating members at the outer sides of 25 the same.

In testimony whereof I affix my signature.

WILLIAM L. BROOKS. [L. s.]
